UNITED STATES PATENT OFFICE.

CHARLES N. MCFARLAND, OF KINGSTON, PENNSYLVANIA, ASSIGNOR TO BURROUGHS ADDING MACHINE COMPANY, OF DETROIT, MICHIGAN, A CORPORATION OF MICHIGAN.

ADDING-MACHINE.

No. 911,060.

Specification of Letters Patent.

Patented Feb. 2, 1909.

Application filed September 1, 1908. Serial No. 532,942.

To all whom it may concern:

Be it known that I, CHARLES N. MCFARLAND, a citizen of the United States, residing at Kingston, in the county of Luzerne 5 and State of Pennsylvania, have invented certain new and useful Improvements in Adding-Machines, of which the following is a specification.

The chief object of the present invention is 10 to provide adding machines and the like with an attachment which will serve the purpose of counting the number of operations of the machine in accumulating items, as for example in listing bank checks and accumulating 15 the total thereof. The invention aims to provide an item counter for machines of this character which will have sufficient capacity to serve for any reasonable length of the listing operations and can be readily reset to 20 zero for a new series of operations. It should be understood at the outset that the purpose is not to register every operation of the machine, as for example every vibration of the operating handle in hand-operated 25 machines, because this would not subserve a particularly useful purpose, inasmuch as blank or spacing strokes are frequently taken in the ordinary use of machines of this character and furthermore total printing requires 30 separate operations of the machine and there would be no special object in keeping count of the number of times the machine might be operated to take a total. The present invention does not, therefore, provide simply for 35 the application of a counting or registering attachment to adding machines for the purpose of showing how many times the machine may have been operated, but entails instrumentalities whereby an accurate account 40 may be kept of those operations of the machine which record or register the separate items whose sum is to be obtained through the operations of the accumulating mechanism of the machine. Thus, the invention 45 provides automatic means for showing the total number of checks for example which have been listed in arriving at the state of a depositor's account in a bank. This is referred to merely as one example of the uses 50 to which such an attachment may be put and it will be obvious that it can be advantageously employed in connection with many other uses to which the commercial adding machine of the present day is put.

With the above stated and incidental objects in view, the invention consists in certain novel features of construction and combinations of parts, the essential elements whereof are recited in the appended claims and a preferred form of embodiment of 60 which is described in detail hereinafter and fully illustrated in the accompanying drawings forming part of this specification.

Of said drawings, Figure 1 represents, partly in longitudinal section and partly in 65 side elevation, a sufficient portion of an adding and listing machine to show the manner of coöperation therewith of the present invention; and Fig. 2 represents the same machine in plan view with a portion of the key- 70 board broken away.

In the present instance, the invention is illustrated and described as applied to that type of adding and listing machine known as the Burroughs and typified, for example in 75 Letters Patent No. 504,963, issued September 12, 1893. This type of adding machine is well known, being disclosed in a number of prior patents in addition to the one just mentioned, and also being extensively employed 80 in banks and commercial establishments. It will not, therefore, require detailed description and the present specification will simply refer to those parts of a Burroughs adding machine with which the present invention is 85 more or less closely associated. In machines of this type, amount keys 291 are arranged in a number of parallel rows or series, the keys of each row being numbered from 1 to 9 and in an operation for adding and printing an 90 item the keys representing the amount are depressed and then a driving shaft is operated either by hand or by power to cause the addition of the amount and the listing of the same. The keys 291 act through levers 217 95 to set stops for controlling the extent of movement of the recording and registering or accumulating devices and a set of these levers 217 below any row of keys operate in slots of a sliding strip or plate 214 which in 100 connection with the latch 228 constitutes means in the nature of a detent to hold the key of that row depressed during so much of the operation of the machine as must be controlled by the stop, set by the key. The 105 strips 214 are formed with depending lips or lugs 214* which overlie the front side of a universal cross rod 402 forming part of the

bail comprising in addition to said rod side arms 424, one of which appears in Fig. 1. Spiral springs 402*, one of which appears in Fig. 1, serve to draw said bail forward, the latter being pivotally mounted at its lower end upon a cross shaft or rod 400. It will be seen, however, that upon depressing any one of the keys 291 in any one of the rows or series this bail will be drawn rearwardly by reason of the action of one of the lips 214*, against the universal rod 402. This bail has been heretofore employed in machines of this character, but its previous functions need not be here described. For the purposes of the present invention, the customary movements of the bail are availed of to establish an operative connection between the operating mechanism of the machine and the item counter which is preferably attached to the casing of the machine at the upper left hand part thereof, as shown in Fig. 2, where the count can be easily read through the casing 1690 of the item counter. The interior mechanism of the latter may be of any well known character, whereby, for example, the oscillations of a driving shaft protruding from said casing will cause step by step advance of one numeral wheel or disk and each complete revolution thereof will be carried to the adjacent numeral disk and so on through as many disks as desired. In the present instance, the item counter is shown as equipped with four numeral disks 1630 so as to afford a capacity of 9,999 counts. The reference numeral 1633 designates a knob or handle by which the said numeral disks or wheels may be turned to zero in any well known manner which requires no detailed description, and the reference numeral 1601 designates the oscillatory driving shaft which projects through the casing 1690 and in the present instance through a bushing 1631 occupying a boss 1629 on the casing of the machine, the item counter being secured in place on the latter by means of a knurled collar 1636 screwed upon said bushing and against said boss.

The driving shaft 1601 has secured to it a crank arm 1611 with a roll-bearing wrist pin 1612 projecting laterally therefrom, as shown in Fig. 2. On the opposite side of said crank arm there is a laterally projecting stud 1653, to which is attached one end of a spiral spring 1685, the opposite end of which is secured to a stationary support in the casing of the machine, said spring serving to normally draw the crank arm rearwardly. Forward movement of said crank arm causes advance of the primary wheel of the item counter in a well known manner, and the subsequent retraction of said crank arm by the spring prepares the counter for the next advance of said primary wheel. The forward movement of the crank arm is effected in the present instance through the instru-

mentality of a link 1619 which, at its rear end takes the form of a hook designed to engage the rear side of the wrist pin 1612. At its forward end this link is pivotally connected with an upward extension of one side plate 70 or arm 613 of the usual restoring frame of a Burroughs adding machine. This frame is customarily mounted to rock or swing upon a shaft 600 and in each operation of the machine goes through a regular and uniform extent of oscillation through appropriate connection with the shaft 300 of the adding machine, to which shaft the driving power is applied. It will not be necessary to enter into the details of this operation. Suffice it to say that the regular and uniform oscillation of this restoring frame is availed of to produce oscillation of the crank arm 1611 of the item counter, through the medium of the link 1619, which, however, is not normally in position for engagement with said crank arm. Its engagement therewith is controlled from the amount keys 291, so that only when one or more of said keys has been depressed, will there exist an operative relation between the item counter and the operating mechanism of the machine, hence only when the machine is registering or recording an item will count be made of the operation.

The manner in which the operative connection between the operating mechanism of the machine and of the item counter is controlled from the keys is as follows: The bail, composed of the universal rod 402 and the side plates 424, has one of its side plates connected by a link 1620 with one arm of a bell crank lever 1621 mounted upon the cross shaft or rod 602, the other arm of said bell crank lever carrying a roller-equipped pin or stud 1622 engaging a longitudinal slot 1623 in the link 1619. The link 1620 is, of course, pivotally connected with the bail and the bell crank lever and when said bail is moved rearwardly by the depression of an amount key the bell crank lever will be correspondingly rocked rearwardly through the medium of said link and thereby the link 1619 will be elevated by reason of the engagement of the roller-equipped pin 1622 with the upper side of the slot 1623. This will have the effect of locating the hook-shaped rear end of the hook 1619 behind the wrist pin 1612 of the item counter crank 1611. It results that when the machine is operated and the restoring frame 613 swung rearwardly the link 1619 will be drawn forwardly and with it the said crank arm, whereby a count is made of the operation. At the conclusion of the machine's operation, the latch 228 is displaced in the usual manner and the strip or plate 214 slid to its normal position, the bail 402—424 being drawn forward by its springs 402*. Thus, the link 1619 is again depressed and the op-

erative connection broken between the operating mechanism of the machine and the item counter.

It will be seen that the construction above described provides for counting up the number of operations of the machine in accumulating or recording items and that no other operations of the machine affect the item counter and thus the objects primarily stated are accomplished. It will, however, be understood that the form of embodiment herein disclosed is susceptible of considerable modification and that the invention is by no means confined to this particular construction. Hence in claims which follow, the essential elements of the invention are recited without limitation to details.

What is claimed is:

1. In a machine of the character described, the combination with accounting mechanism and actuating means therefor, of an item counter operable by said actuating means, such operability being controlled by said accounting mechanism.
2. In a machine of the character described, the combination of accounting mechanism including manipulative amount-determining devices, actuating means for said accounting mechanism, and an item counter operable by said actuating means, such operability being controlled by said accounting mechanism.
3. In a machine of the character described, the combination of accounting mechanism including manipulative amount-determining devices, actuating means for said accounting mechanism, and an item counter operable by said actuating means, such operability being controlled by said accounting mechanism through manipulation of said amount-determining devices.
4. In a machine of the character described, the combination of accounting mechanism including manipulative amount-determining devices and differential accounting elements controlled thereby, actuating means for said accounting mechanism, and an item counter operable by said actuating means, such operability being controlled by said amount-determining devices and the operation of said item counter requiring operation of the said differential accounting elements.
5. In a machine of the character described, the combination with main operating mechanism; of an item counter, operating connections between the same and said main operating mechanism, and amount keys controlling said connections.
6. In a machine of the character described, the combination with main operating mechanism; of an item counter, separable operating connections between the same and said main operating main mechanism, and amount keys for establishing said connections during an accounting operation of the machine.
7. In a machine of the character described, the combination of main operating mechanism, an item counter normally disconnected therefrom, and amount keys for establishing an operative connection between said item counter and said main operating mechanism during an accounting operation.
8. In a machine of the character described, the combination with a reciprocatory actuator, of an item counter having a reciprocatory driving member, and a key-controlled coupling between the latter and the said reciprocatory actuator.
9. In a machine of the character described, the combination with a reciprocatory actuator, of an item counter having a reciprocatory driving member, a normally disengaged link for connecting the latter with said reciprocatory actuator, and amount keys controlling said link.
10. In a machine of the character described, the combination with an oscillatory actuator, of an item counter having an oscillatory driving member, and a key-controlled coupling between the latter and the said oscillatory actuator.
11. In a machine of the character described, the combination with an oscillatory actuator, of an item counter having an oscillatory driving member, a normally disengaged link for connecting the latter with said oscillatory actuator, and amount keys controlling said link.
12. In a machine of the character described, the combination of an item counter having an oscillatory driving member, an oscillatory actuator, a link joined to the said oscillatory actuator and adapted to engage the said oscillatory driver of the item counter, and amount keys for establishing such engagement during an accounting operation.
13. In a machine of the character described, the combination of an item counter having an oscillatory driving member, an oscillatory actuator, a slotted link joined to the oscillatory actuator and adapted to engage the oscillatory driver of the item counter, a lever engaged with the slotted part of said link, and amount keys controlling said lever.
14. In a machine of the character described, the combination of an item counter having an oscillatory driving member, an oscillatory actuator, a slotted link joined to the oscillatory actuator and adapted to engage the oscillatory driver of the item counter, a bell crank lever, one arm of which is engaged with the slotted part of said link, and amount keys connected with the other arm of said lever.
15. In a machine of the character described, the combination of an item counter having an oscillatory driving member, an oscillatory actuator, a slotted link joined to the oscillatory actuator and adapted to engage the oscillatory driver of the item counter, a

ball crank lever, one arm of which is engaged with the slotted part of said link, a bail linked to the other arm of said lever, and amount keys controlling said bail.

16. In a machine of the character described, the combination of an item counter having an oscillatory driving member, an oscillatory actuator, a slotted link joined to the oscillatory actuator and adapted to engage

the oscillatory driver of the item counter, a bell crank lever, one arm of which is engaged with the slotted part of said link, a bail linked to the other arm of said lever, amount keys, and key detents engaged with said bail.
